SPOOL

Frederick J. Bieber, Minneapolis, Minn., assignor
to Acrometal Products, Inc., Minneapolis,
Minn., a corporation of Minnesota

Application September 15, 1952, Serial No. 309,668

3 Claims. (Cl. 242—118)

1

My invention relates generally to winding spools, bobbins or drums for winding of textile threads, wire, and the like.

In particular, my invention relates to improvements in winding spool constructions whereby the effective life of a winding spool may be materially increased.

In the textile industry, or in the manufacture of wire, the finished thread or wire filament is generally wound upon a winding drum or spool from whence the same is subsequently removed and wound upon other spools for transportation, sale, or otherwise disposed of. Spools of the type described are usually mounted for rotation on tapered rotary spindles, the spools having tapered central apertures by means of which frictional locking engagement is effected between the spool and the spindle. Obviously, when a spool is mounted on a rapidly rotating spindle, slippage occurs therebetween until the spool has been moved axially of the spindle to effect frictional locking therebetween. Continuous mounting and dismounting of the spool upon the spindle will, over a period of time, cause the tapered mounting aperture in the spindle to wear to a degree which necessitates replacement of the spool. Inasmuch as these spools rotate at a relatively fast rate, they must be carefully made and balanced for the most efficient operation. Hence, when the spool becomes worn to the point where it must be discarded, the cost of replacement thereof is sometimes prohibitive. The primary object of my invention is, therefore, the provision of a winding spool as set forth, having a relatively inexpensive disposable spindle engaging bearing element which, when worn out, can be quickly and easily replaced in the spool at a minimum cost.

Another important object of my invention is the elimination of mechanical joints between the winding drum element and end flanges of a winding spool and resultant joint openings wherein a portion of thread or wire filament may become lodged when being wound thereon, thereafter with smooth and uniform unwinding and often resulting in breakage of the filament.

Another object of my invention is the provision of a winding spool as set forth, which can be manufactured at a minimum cost, which is highly efficient in operation, and which is rugged in construction and durable in use.

The above and still further highly important objects and advantages of my invention will become apparent from the following detailed specification, appended claims, and attached drawings.

2

Referring to the drawings which illustrate the invention, and in which like characters indicate like parts throughout the several views:

Fig. 1 is a view in side elevation of a winding spool built in accordance with my invention;

Fig. 2 is an axial section taken substantially on the line 2—2 of Fig. 1;

Fig. 3 is a view partly in end elevation and partly in section taken substantially on the line 3—3 of Fig. 2; and

Fig. 4 is a view in end elevation as seen from the right to the left with respect to Fig. 1.

In the preferred embodiment of the invention illustrated, a spool is shown as comprising a tubular winding drum element 1 having integrally formed radially outwardly projecting circumferential flanges 2 and 3 at opposite ends thereof. The winding drum element is preferably made from a single piece of cast metal such as aluminum or the like and machined to provide smooth outer surfaces, and a cylindrical inner wall surface 4 concentric with the outer surface 5 of the winding drum element. The flanges 2 and 3 at their peripheral edge portions are covered by rims 6 and are preferably made from nylon or other suitable material.

Mounted in opposite end portions of the interior of the winding drum element 1 are a pair of bushings or the like 7 and 8. The interior wall 4 of the drum element 1 is diametrically enlarged at its opposite end portions to provide recesses 9 and 10 respectively for the reception of diametrically enlarged heads 11 and 12 of the bushings 7 and 8, respectively. The bushings 7 and 8 are held against axial inward movement by seating of the enlarged head portions 11 and 12 thereof in the bottom of their respective recesses 9 and 10, and are anchored against axial outward movement and against rotation with respect to the spool by scoring as indicated at 13 and 14, both the winding drum and the bushings are scored with an interlocking arrangement so that a permanent connection is effected therebetween. The bushings 7 and 8 are preferably made from steel or other material suitable for the purpose. The bushing 7 is provided at its outer end with a central outwardly opening recess 15 and a central aperture 16 concentric with the recess 15 and the winding spool. The side walls of the recess 15 and the aperture 16 define the edges of a stop shoulder 17, the purpose of which will hereinafter become apparent. In like manner, the bushing 8 is provided with an axially inwardly opening central recess 18 and a central aperture 19 concentric with the recess 18 and the spool.

Obviously, the aperture 19 is axially aligned with the aperture 16 and bushing 7 until, with reference to Fig. 2, it will be seen that the aperture 19 is of greater diameter than the aperture 16. The side wall of the recess 18 and the aperture 19 define the outer and inner edges respectively, of a stop shoulder 20 in the bushing 8. Further, the said outer recess 18 is provided with a pair of radially inwardly opening notches 21 which are in diametrically opposed relationship and 10 which extend from the outer edge of the bushing 8 to the bottom of the recess 18. It will be noted 20 that the outer surface of the bushings 7 and 8 lies substantially in the same plane as the outer surface of the flanges 2 and 3, so that the shoulders 17 and 20 are axially inwardly spaced from the extreme opposite ends of the spool.

Extending between the bushings 7 and 8 is 25 a tubular core or bearing element 22 and a head 23 at one end thereof and a reduced diameter portion 24 at its other end portion. As shown in, Fig. 2, the bearing element 22 extends axially of the spool and slidably therein the head 23 thereof engaging the stop shoulder 20 whereby to be limited against axial movement in one direction, means for locking the bearing element 22 against axial movement in the opposite direction, comprises a conventional split ring 25 which is releasably set in a circumferentially extended groove 26 in the outer wall of the reduced portion 24 of the tubular bearing member 22 and immediately axially outwardly of the stop shoulder 17 whereby to lock the bearing member 22 against axial movement in the opposite direction. Means for locking the tubular bearing 30 member against rotation with respect to the bushings and spool comprises a pair of diametrically opposed lugs or ears 27 which are formed integral with and which extend radially outwardly of the head 23 into the opposed notches 21 when the bearing member 22 is mounted in the spool. The relatively small faces or aperture 16 in the bushing 7 as compared to the diameter 16 in the main body portion of the tubular bearing 35 22 prevents the bearing element 22 from being inserted into and properly anchored in the spool in but one direction. Thus, the spool will not be turned end for end when removed from one level or location and relocated on a different device for unwinding of the thread or wire secured thereon.

The tubular bearing element 22 is formed adjacent its opposite ends with tapered bearing surface portions 28 and 29 which define axially spaced surface portions of a cone extended 40 axially through the bearing element. The taper of the bearing wall surface portion 28 and 29 is identical to the taper of a rotary spindle on which the spool is adapted to be mounted in practice, said spindle being shown by dotted lines in Fig. 2 and indicated by the reference character A. Normally, a cup-like ferrule 30 is pressed into the recess 15, said ferrule having a central opening 31 through which the spindle 45 A projects when the spindle is mounted thereon. The ferrule 30, not only provides a finished appearance to the adjacent end of the spool, but also serves as an indicator to the operator as to which end of the spool should be applied to the rotary spindle A.

As above indicated, when the winding spool has been in prolonged use, friction between the relatively hard spindle A and the bearing surfaces of the spool during the application of the spool to the spindle, causes sufficient wear on

the bearing surface to necessitate the discarding of the spools which are otherwise still in good condition. However, with my novel spool construction, when the bearing surface portions 28 and 29 become worn to a point where efficient operation is no longer possible, the operator merely removes the ferrule 30 from the recess 15, and the snap ring 25 from the adjacent end of the tubular bearing element. Thereafter the tubular bearing element 22 is removed from the spindle and a new bearing element 22 installed therein. Thus, the spool is again placed in condition for efficient operation without appreciable loss of time and at a minimum of expense, inasmuch as the bearing element 22 is inexpensive to produce as compared to the cost of producing an entire spool with integrally formed bearings. In fact, the spool 1, under normal conditions, will have an effective life equal to a number of tubular bearing elements. Obviously, with the construction described herein, the relatively light weight of my novel spool will be a contributing factor to its own life by reason of the fact that the frictional load imposed upon the bearing surface when the spool is applied to the rotary spindle is maintained at a minimum.

My invention has been thoroughly tested and found to be completely satisfactory for the accomplishment of the objectives set forth; and while I have shown and described a commercial embodiment of my novel spool structure, it will be understood that the same is capable of modification without departure from the spirit and scope of the invention as defined in the claims.

What I claim is:

1. In a spool of the class described, a tubular winding drum element having a radially outwardly projecting circumferential flange at each end thereof, a pair of axially aligned bushings one each within an opposite end portion of the drum element, said bushings having axially aligned outwardly opening central recesses concentric with said winding drum element and reduced aligned central apertures extending axially inwardly from the bottoms of the recesses which define stop shoulders inwardly spaced from the opposite ends of said drum element, a tubular bearing element axially slidable into and out of said apertures, means on one end of said bearing element and the adjacent bushing for locking said bearing element against rotation with respect to said bushings and engageable with one of said stop shoulders to limit axial movement of said bearing element in one direction, and releasable means on the other end of said tubular bearing element cooperating with the stop shoulder on the other of said bushings to lock said bearing element against axial movement in the opposite direction, said bearing element having an inner wall portion tapering toward one of its ends, whereby said spool may be mounted on a tapered driving spindle for common rotation therewith.

2. In a spool of the class described, a tubular winding drum element having an integrally formed radially outwardly projecting circumferential flange at each end thereof, a pair of axially aligned bushings one each contained within an opposite end portion of the drum element, means anchoring said bushings against axial sliding and rotary movement with respect to the drum element, said bushings having axially aligned outwardly opening recesses concentric with said drum element and aligned apertures

extending axially inwardly from the bottoms of the recesses, the side walls of said recesses and the apertures defining the outer and inner edges respectively of stop shoulders inwardly spaced from the opposite ends of said drum element, a tubular bearing element axially slideable into and out of said apertures, a head on one end of said bearing element engageable with one of said stop shoulders for limiting axial movement of said bearing element in one direction, releasable means on the other end of said tubular bearing element cooperating with the stop shoulders of the other of said bushings to lock the bearing element against axial movement in the opposite direction, and means on said bearing element and one of said bushings for locking the bearing element against rotation with respect to the bushings, said bearing element having an inner wall portion tapering toward one of its ends, whereby said spool may be mounted on a tapered driving spindle for common rotation therewith.

3. In a spool of the class described, a tubular winding drum element having an integrally formed radially outwardly projecting circumferential flange at each end thereof, a pair of axially aligned bushings one each anchored within an opposite end portion of the drum ele-

ment, an axially displaceable tubular bearing element having its opposite ends each concentrically mounted in one of said bushings, and means releasably locking said bearing element against rotary and axial sliding movements with respect to said bushings, said bearing element having axially spaced inner wall surface portions tapering toward one of its ends, said inner wall surface portions defining axially spaced surface portions of a cone extending axially therethrough, whereby said spool may be frictionally mounted on a tapered driving spindle for common rotation therewith.

FREDERICK J. BIEBER.
